UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

WARP STOP MOTION FOR LOOMS.

Application filed March 16, 1926. Serial No. 95,011.

This invention relates to looms and more particularly to means for effecting loom stoppage when any one of the warp threads breaks or becomes too slack.

5 It is now the common practice to provide looms with warp stop mechanism of the type wherein warp detectors or drop wires are supported by the warp threads and are normally held thereby out of the path of a 10 vibrating feeler, and when a warp thread breaks or becomes too slack, the movement of the feeler is arrested to effect loom stoppage.

The mechanism now commonly provided to stop the loom when the rocking movement 15 of the feeler is arrested by a drop wire, consists of a pivoted dog that is mounted upon a movable carrier and the dog is constructed to be moved into position to engage a traveling bunter when the loom is to be stopped.

20 The means employed heretofore for placing the dog under the control of the feeler usually consists of a plunger that abuts against the dog to lift it, and an actuator for shifting the plunger.

25 This mechanism employed heretofore for shifting the dog is open to the objection that the angle through which the dog moves will vary with the movement imparted to the dog operating plunger, with the result that the operating movement imparted to the 30 plunger does not always properly position the dog.

To overcome this difficulty, the present invention relates to means controlled by the 35 warp stop mechanism and which is so constructed that the dog which engages the bunter is shifted to the same position irrespective of the amount of movement imparted to the dog actuating means, and as a 40 result, proper positioning of the dog upon the occurrence of a warp fault is assured.

The invention and the various novel features thereof will best be made clear from the following description and the accompanying drawings of one good form thereof.

In the drawings:—

Fig. 1 is a side view of a loom with parts in section, and containing the present invention;

50 Fig. 2 on an enlarged scale is a perspective view of the dog carrier and associated parts;

55 Fig. 3 is a longitudinal sectional view through the carrier of Fig. 2, showing the dog in its inactive position;

Fig. 4 is a view similar to that of Fig. 3 but showing the dog in its active position; and

Fig. 5 is a perspective view of the warp stop mechanism and controller associated 60 with the feeler.

The loom frame 1 may be of usual construction and is provided with the lay 2 supported by the lay swords 3. Mounted on the loom frame is the shipper 4 which, 65 when the loom is in operative condition, is retained, as usual, in a notch 5 on the shipper stand. Pivotal mounted on the loom frame at 6 is a shipper knock-off 7, the end 8 of which normally rests against the front 70 portion of the shipper 4 and is adapted to disengage it from its holding notch 5 to effect loom stoppage.

The warp stop mechanism may be of any 75 usual type and as shown comprises the side bars 9 extending transversely of the loom and upon which the warp threads *a* rest. Each of the warp threads *a* supports a drop wire 10, and so far as the invention in the present case is concerned, such drop wires 80 may be of any usual type.

The side bars 9 are supported by brackets 11 mounted at the opposite sides of the loom and these brackets are provided with a downwardly extended portion 12 in which 85 the rock shaft 13 is pivotally mounted. Rigidly secured to this shaft are the arms 14 which support and rock the feeler 15 in a well-known manner. The means shown for rocking the shaft 13 consists of the cam member 16 rigidly secured to the shaft and which engages a complementary cam member or controller 17 loosely mounted on the rock-shaft and actuated to effect rocking movement of the rock-shaft by means of 90 an arm 18 which may be rocked by a rod 19, as usual in this type of warp stop mechanism.

Between the sleeve of one of the arms 14 and the cam member 17 is confined a spring 20, the construction being such that 100 during normal operation of the loom, the feeler 15 will be given a rocking movement below the drop wires 10, but on the occurrence of a warp fault, as when a warp thread becomes broken or too slack, the supported drop wire 10 will fall into the path of the feeler 15 and stop the rocking shaft, whereupon the controller 17 will be moved 105 longitudinally of the rock shaft.

This movement of the controller 17 longi- 110

tudinally of the rock-shaft, in the construction shown, serves to impart a sliding movement to a flexible wire 21 within the flexible sheath 22. One end of the sheath 22 is secured to the bracket 12 and an end of the wire 21 rests against the controller 17. The arrangement is such that movement of the wire 21 within the sheath 22 serves to shift a dog into position to effect loom stoppage by releasing the shipper 4, as will presently appear.

In the construction shown, the shipper knock-off 7 is controlled by a rod 23 that extends from the knock-off to a dog carrier 24. This carrier is mounted for sliding movement to effect loom stoppage, and may be supported by a bracket 25 to which it is adjustably secured by a clamping bolt 26 that extends through an elongated slot 27 in the bracket. The bracket 25 may be slidably mounted upon the brake applying rod 28, that is, supported at one side of the loom.

Within the carrier 24 is pivotally mounted the dog 29 having the pivot pin 30, and the parts are so positioned that when the dog 29 is rocked to the position shown in Figs. 1 and 4, it will be struck by a bunter 31 secured to the lay 2. The arrangement is such that engagement of the bunter 31 with the dog will force the carrier 24 in a left-hand direction, view Fig. 1, and this will pull the rod 23 to release the shipper 4.

The construction described whereby loom stoppage is effected by moving a dog into position to be engaged by a traveling bunter is old, but as above stated, the mechanism employed heretofore for moving the dog to its bunter engaging position has been open to the objection that it would not accurately shift the dog to the desired position, because the movement imparted to the dog would vary heretofore with the amount of movement imparted to the dog actuating means.

In order to overcome this difficulty, the present invention is directed to dog operating means which is so constructed that variation in the amount of movement imparted to the dog actuating means will not vary the position to which the dog is shifted, and to this end the carrier 24 is provided with a slide 32, shown as positioned below the dog and supported for sliding movement by the bar 33 to which it is rigidly secured and the ends of which bar are received in aligned holes in the carrier. The slide 32 is provided with a cam portion 34 positioned to engage a shoulder 35 upon the dog. The arrangement is such that as the slide 32 is shifted from the position shown in Fig. 3 to that of Fig. 4, it will move the dog to its operative position of Fig. 4, and it is important to note that as the cam portion 34 wipes under the shoulder 35, it will lift the dog a predetermined amount, irrespective of slight variations in the amount of sliding

movement that may be imparted to the slide. The portion of the shoulder 34 which rests upon the cam when the parts are in the position shown in Fig. 4 should lie approximately parallel to the axis of the bar 33, as shown, so that the cam 34 may move a substantial distance along the dog without changing the position in which the latter is supported.

The slide 32 is urged in one direction by the spring 36 and is moved in the opposite direction by the plunger 37 mounted within the sleeve 38, which sleeve is secured in the carrier by the bolt 39, and movement is imparted from the actuator 17 to the plunger 37 by the flexible wire 21, an end of which rests against the plunger.

From the foregoing it will be seen that the slide 32 serves accurately to position the dog 29 and that minor variations in the amount of movement imparted to the slide will not vary the position to which the dog is shifted because the lower surface of the shoulder 35, while approximately parallel to the axis of bar 33 as stated, has a sufficient inclination downwardly towards the end of the dog to compensate for the variation in distance of the cam 34 from the axis 30 of the dog, but such inclination is, of course, slight.

What is claimed is:—

1. In a loom, the combination of warp stop mechanism, a controller adapted to be moved on the occurrence of a warp fault, a dog carrier mounted for movement to and from a position to effect loom stoppage, a dog pivotally mounted upon said carrier for movement into and out of position to be struck by a traveling bunter, a slide mounted upon the carrier for sliding movement in a direction longitudinally of the dog and having a cam portion to engage the dog to rock the same to its bunter engaging position, as the slide moves longitudinally of the dog, and means actuated by the controller for moving the slide to the dog actuating position.

2. In a loom, the combination of warp stop mechanism, a controller adapted to be moved on the occurrence of a warp fault, a dog carrier mounted for movement to and from a position to effect loom stoppage, a dog mounted upon said carrier for movement into and out of position to be struck by a bunter and having a shoulder, a slide mounted upon the carrier for sliding movement in a direction substantially parallel to the dog and having a cam portion positioned to move along said shoulder and thereby lift the dog to its operative position, and a plunger actuated by the controller for moving the slide to the dog lifting position.

3. In a loom, the combination of warp stop mechanism, a controller adapted to be moved on the occurrence of a warp fault, a

- dog carrier mounted for movement to and from a position to effect loom stoppage, a dog pivotally mounted upon said carrier for movement into and out of position to be actuated by a bunter, a slide mounted upon the carrier for movement along a predetermined path relatively to the dog and inter-engaging parts on the dog and slide constructed and arranged so that movement of the slide to different positions along said path will impart the same rocking movement to the dog, and means actuated by the controller for moving the slide.
4. In a loom, the combination of a warp stop mechanism, a controller adapted to be moved on the occurrence of a warp fault, a dog carrier mounted for movement to effect loom stoppage, a dog pivotally mounted upon said carrier for movement into and out of position to be actuated by a bunter, a slide mounted upon the carrier and engaging parts on the slide and dog constructed and arranged to lift the dog the same amount irrespective of the length of movement imparted to the slide, and means actuated by the controller for shifting the slide.
5. In a loom, the combination of warp stop mechanism, a controller adapted to be moved on the occurrence of a warp fault,
- a dog carrier mounted for movement to effect loom stoppage, a dog pivotally mounted upon said carrier for movement into and out of position to be actuated by a bunter and having a shoulder, a slide mounted upon the carrier and having a cam portion positioned to engage said shoulder to lift the dog to a predetermined position and then move past the shoulder without imparting further movement to the dog, and means actuated by the controller for moving the slide.
6. In a loom, the combination of warp stop mechanism, a controller adapted to be moved on the occurrence of a warp fault, a dog carrier mounted for movement to effect loom stoppage, a dog mounted upon said carrier for movement into and out of position to be actuated by a bunter, a slide mounted upon the carrier for movement in a direction longitudinally of the dog and constructed and arranged to shift the dog to the same position irrespective of the amount of movement imparted to the slide, a plunger for shifting the slide, and means actuated by the controller for operating the plunger.

In testimony whereof, I have signed my name to this specification.

HARRY A. DAVIS.
